[57] CLAIM

The ornamental design for a bib, substantially as shown and described.

DESCRIPTION

FIG. 1 is a front elevational view of a bib showing my new design, the neck strap thereof shown in the closed position; the back of the bib being of substantially the same configuration as the front, but without the decorative motif; and

FIG. 2 is a sectional view taken along line 2—2 of FIG. 1.

FIG. 2
